[57] CLAIM

The ornamental design for a combined compost mixing, aerating and removing tool, as shown and described.

DESCRIPTION

FIG. 1 is a front elevational view of a combined compost mixing, aerating and removing tool showing my design; FIG. 2 is a rear elevational view thereof; FIG. 3 is a right-side elevational view thereof; FIG. 4 is a left-side elevational view thereof; FIG. 5 is a top plan view thereof; FIG. 6 is a bottom plan view thereof; FIG. 7 is an enlarged, cut-away elevational view of the bottom portion thereof as seen in FIG. 3; FIG. 8 is a top plan view of the enlarged bottom portion thereof seen in FIG. 7; and, FIG. 9 is an enlarged, cut-away elevational view of an alternative embodiment of the bottom portion of FIG. 3, the remaining views being similar to those shown in the first embodiment.
